UNITED STATES PATENT OFFICE

GUSTAV E. JANSSON, OF WOLLASTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

OIL-FILLED BUSHING

Application filed June 30, 1926. Serial No. 119,724.

This invention relates to electric insulators and more particularly to those of the bushing type which have insulating enclosing casings comprising a number of tubular sections and which are adapted to contain a body of insulating fluid or compound, such as oil.

Considerable difficulty is encountered in this type of bushing in making an oil tight connection between the sections of the outer insulating casing. In my copending applications, Serial No. 119,723, filed June 30, 1926, and Serial No. 110,126, filed May 19, 1926, respectively, I have shown two different methods of connecting insulator sections of this type and some of the features of the insulator embodying the present invention are disclosed therein.

It is an object of this invention to provide an oil-filled insulating bushing having an outer enclosing casing comprising two or more insulating tubes joined together in a permanent fluid-tight manner at their proximate ends.

It is a further object of the invention to provide a fluid-tight insulating bushing having a two piece outer shell which will be cheaper to manufacture and more reliable than the present bushings of this type.

A further object is generally to improve oil-filled bushing type insulators.

Fig. 1 shows an elevation partly in section of an insulator embodying the invention.

Fig. 2 is an enlarged sectional detail of the fluid tight seal provided between the upper and lower insulating sections of the insulator.

Fig. 3 is a sectional view of the insulator taken on lines 3-3 of Fig. 1.

As here shown, the insulating bushing embodying the invention comprises the upper insulating section 10 provided with the usual capes, or petticoats 12, the lower insulating section 14 provided with external

corrugations 16 at the lower end thereof, and the intermediate metal attaching collar or sleeve 18 which surrounds the proximate ends of said sections 10 and 14. The upper insulating section comprises essentially a

porcelain tube having preferably straight

side walls and open at the top and bottom. The lower insulating section comprises a porcelain tube open at the top and tapered at its lower end to provide a restricted passage at the bottom.

The top of the insulator is provided with an oil reservoir consisting of a metal cylinder 20 which is secured in fluid tight relation to the open top of the insulating section 10. The oil reservoir is provided with a cap 24 which is screw-threaded to the upper end of said cylinder 20 and forms a cover for the reservoir. A glass cylinder 26 is disposed within said cylinder 20 and the oil level in the insulator and in the glass cylinder 20 is visible at all times through suitable apertures 28 of the metal cylinder 20. Said reservoir cover 24 is provided with an axial opening through which a conducting stud 32 is adapted to pass freely and said opening is covered against entrance of water by a cover 34 which is screw-threaded on said conductor and which has a depending apron 36 surrounding said opening.

The lower insulating section 14 is provided with a restricted passage in its lower end in which a bushing 38 is secured by means of a body of cement 40. Said conducting stud 32 is adapted to be screw-threaded through and extend beyond said bushing and a lock nut 41 is screwed onto the lower extended end of said conductor to prevent rotation of the stud in the bushing. A packing 42 disposed between the nut and the lower end of the insulating section 14 serves to provide an oil tight seal thereto.

Said metal collar 18 is adapted to provide a mechanical connection between the upper and lower insulating sections and also to provide the support for the insulator. To this end said collar is provided with an integral outstanding flange 44 by which the bushing is adapted to be secured to the casing 45 of any desirable electrical apparatus. The diameter of the collar is adapted to be somewhat larger than that of the insulating sections to provide an annular space therebetween to receive a body of cement 46 by means of which said upper and lower insu-

lating sections are rigidly and permanently fixed within said collar 18. Annular grooves 48 are provided on the inner surface of said sleeve into which the cement is adapted to enter, and those surfaces of the insulating tubes surrounded by the collar may be roughened, thus enhancing the strength of the bond between the sleeve and the insulating sections.

5 Cement, where it is used in oil filled bushings, cannot always be relied upon to maintain a fluid-tight joint because of its inherent porous structure. Consequently, means is provided to prevent the oil within the insulator from seeping through the cemented joint between the insulating sections 10 and 14. Said means comprises an annular packing washer 50 of some suitable yielding material, as cork, disposed between the proximate ends of said insulating sections.

10 It is not necessary to provide a breakable joint intermediate the ends of the insulators since the open top construction permits the assembly of the inner parts of the bushing through the top as is set forth in my co-pending application Serial No. 110,126, filed May 19, 1926. Consequently the joint between the insulating sections 10 and 14 is 15 intended to provide a permanent unitary structure for the enclosing casing of the bushing.

15 In assembling the outer casing, the packing washer 50 is thoroughly coated with an insulating and oil-insoluble resin or gum, such as shellac, which will enter into the pores of the packing and adhere to the unglazed surfaces at the ends of the porcelain insulating sections 10 and 14. The packing is then compressed by applying a substantial pressure at the outer ends of the two insulating sections while one or more coats 52 of shellac is applied to the outer circumference of the packing and in the 20 immediate vicinity of the joint. When the shellac has hardened and while the packing is still held in compressed relation between the insulating sections, the cement 46 is put in place between the sleeve 18 and the porcelain sections and allowed to set so that when the cement has set the packing 50 is held in a permanent state of compression thereby 25 between said insulating sections.

30 The insulator shown herein for purposes of illustrating the invention is made up of two porcelain sections although it is obvious that any number of sections could be secured together to provide a fluid-tight tube of any desired length.

35 The construction may be modified in a great many ways without departing from the scope of the invention.

I claim:

40 1. An oil filled insulating bushing having an outer enclosing casing including two

45 axially disposed insulating tubes and means permanently connecting said tubes together in an oil tight manner including a metal sleeve surrounding said tubes at their proximate ends and spaced therefrom, a body 50 of cement disposed within the space between said sleeve and said tubes, and a packing of compressible material disposed between and held in compression by the proximate ends of said tubes and the cement, and components including a conductor disposed within said joined insulating tubes, said bushing having an entrance thereto through the end of one of said tubes which is at least as large as the largest diameter of 55 said components, so that said components can be withdrawn through said entrance without breaking the oil-tight connection between the tubes.

5. An oil filled insulator having two 60 axially aligned insulating members, a sleeve disposed around the proximate ends of said members and spaced therefrom, a body of cement contained in the space between said sleeve and said members to bind said sleeve 65 and members together, and compressible packing means disposed between the proximate ends of said members and held in a compressed state by said insulating members and cement, and an oil proof sealing 70 coating applied to the proximate ends of said insulating members and overlying said packing means.

6. An oil filled insulator having two adjacent insulating members, a collar disposed around the proximate ends of said members and spaced therefrom, a compressible packing disposed between the proximate ends of said insulating members and held in compression by said members, and a body of cement contained in the space between said members and collar and holding said insulating members and said packing in compressed condition.

7. The method of making an oil-tight 100 joint between two porcelain sections having contiguous ends which consists of placing a compressible packing between the proximate ends of said sections, applying a coat of oil-proof sealing material to the outside of said sections in the vicinity and over the outer edge of said packing, and binding said sections rigidly together by a mass of cement which surrounds both sections and the joint therebetween and is adherent to said sections and a metal collar which surrounds the sections at the joint between them.

8. The method of forming an oil tight joint between two porcelain sections of an insulator which consists of providing a compressible packing between the contiguous faces of the sections, applying a pressure on said sections to compress said packing, coating the outer surface of the insulator in the vicinity of said joint with an insulating and 110 115 120 125 130

oil-impermeable sealing substance, cementing a connecting sleeve to the outside of said insulating sections in the vicinity of said joint, and holding the packing in compression until the cement hardens.

5 6. An oil-filled insulator including two axially aligned insulating members spaced apart by a compressible packing washer, an attaching collar disposed about the proximate ends of said members and spaced therefrom, and a body of cement adapted to occupy said space and fix said members permanently to said collar with said packing washer in a compressed condition therebetween.

10 7. An insulator comprising two aligned insulating tubes, a compressible packing washer disposed between the contiguous ends thereof and held in compression by said tubes, and an external connecting sleeve cemented to said tubes intermediate the ends of said insulator and arranged to hold said tubes permanently in pressure engaging relation with said washer.

15 8. An oil filled insulating bushing including an outer enclosing casing comprising two axially aligned insulating shells, and means comprising a nonbreakable joint permanently connecting said shells together in an oil-tight manner including a metal sleeve surrounding and spaced from said shells at their proximate ends, a packing of compressible material disposed between and held in compression by the proximate ends of 20 said shells, and means to hold said shells and said compressible packing in the aforesaid relation comprising a body of cement disposed within the space between said sleeve and said shells.

25 40 In testimony whereof, I have signed my name to this specification.

GUSTAV E. JANSSON.
